Patented Mar. 12, 1918.

UNITED STATES PATENT OFFICE.

WILLIAM H. BRADSHAW, OF PHILADELPHIA, PENNSYLVANIA, ASSIGNOR TO WILLIAM THOMPSON PLUMMER, OF PHILADELPHIA, PENNSYLVANIA.

METHOD OF STRETCHING AND COILING BELTS.

1,258,648.

Specification of Letters Patent. Patented Mar. 12, 1918.

Application filed May 4, 1917. Serial No. 166,317.

To all whom it may concern:

Be it known that I, WILLIAM H. BRADSHAW, a citizen of the United States of America, residing at Philadelphia, in the 5 county of Philadelphia and State of Pennsylvania, have invented certain new and useful Improvements in Methods of Stretching and Coiling Belts, of which the following is a specification.

10 This invention relates to a method of stretching and coiling belts preferably during the process of manufacture or prior to their actual commercial use.

One of the objects of the present invention is to provide a simple and practical process of treating belts to permanently remove the stretch therein. A further object is to provide a continuous method or process 15 of stretching and coiling belts which will be commercially practicable and more efficient, reliable and satisfactory than processes now 20 in use.

Other objects will be in part obvious from the annexed drawing and in part indicated 25 in connection therewith by the following analysis of this invention.

This invention accordingly consists in the several steps and their various relations to one another, as well as their relations to 30 the features of construction, combination of parts and in the unique relations of the members, and in the relative proportioning and disposition thereof; all as more completely outlined herein.

35 To enable others skilled in the art so fully to comprehend the underlying features thereof that they can perform the same in apparatus involving numerous modifications in structure and relation, drawings depicting 40 a preferred form of apparatus have been annexed as a part of this disclosure, in which is shown semi-diagrammatically a side elevation thereof.

Referring now to the drawing in detail, 45 1, 2 and 3 denote three sets or pairs of stretching and calendering rollers. It is, of course, to be understood that more or less sets may be employed as desired, six sets being preferred. The belt 4 passes over and 50 between these rolls, as indicated and the several rolls are connected by means of power transmitting mechanism of any desired type, such as chains and sprockets in a manner to produce a progressively increasing 55 peripheral speed of each set with respect

to the previous set. This progression need not be constant or uniform. Thus, for example the first set is provided with a sprocket 5 and chain 6 connected with a sprocket 7 upon the second set. This same 60 shaft is provided with a slightly larger sprocket 8 which is connected by means of chain 9 with a sprocket 10 upon the third set. The same is true of the lower rolls of each set. Both rolls of the first set are 65 driven from a shaft 11 provided with bevel gearing 12 or the like adjacent the set, as well as gearing 13 communicating with a main power shaft 14. A source of power indicated by the belt and pulley 15 is intended 70 to rotate the shaft 14.

It will thus be seen that as the shaft 14 rotates power will be transmitted through the shaft 11 to both rollers of the first set. This power is further transmitted through 75 chains 6 to the rollers of the second set and thence through chains 9 to the rollers of the third set and so on if more sets are employed. The second set is rotated at a slightly higher rate of speed than the first while the third 80 set is designed to rotate at a slightly higher speed than the second set. This produces a continuous stretching of the belt at the points 16 and 17 where it passes from one set to another prior to its passage to the 85 reeling or coiling mechanism shown at the right of the drawing.

While the rollers of the sets as shown are of the same size and the sprockets of different size, it is clear that the rollers may be 90 of increasing size and the sprockets of the same size to produce the same result of increasing peripheral speed.

The reeling or coiling mechanism for the belt which should be immediately adjacent the stretching mechanism comprises rollers 20 and 21 connected by means of chain and sprocket mechanism 22-23 driven from a secondary shaft 24 connected by means of a bevel gear or the like 25 to the main power 95 shaft 14. The coiled belt is indicated at 26 and is held down with a high degree of pressure upon the roll 21 by means of a presser roll 27 guided as by a frame 28 of any desired type. The rollers 20 and 21 are slightly 100 different in diameter and thus the periphery of the roller 21 travels at a slightly greater speed than the periphery of the roller 20, thereby tending to push the coil ahead faster than the belt is fed by the roll 20, thus main- 105 110

taining the belt in its stretched condition and coiling it very tightly in that stretched condition. The roller 20 is preferably driven at a slightly greater peripheral speed than the roller 3 in order to produce a stretching of the belt adjacent the point 30, thus preventing recovery.

If desired the rollers may be of the same size and driven by differential gearing although the structure shown is preferred. These mechanisms above described merely illustrate semi-diagrammatically one of a number of different forms of apparatus adapted to carry out the process herein described.

It may have been attempted to stretch belts by the mechanism shown at the left of the drawing and it also may have been attempted to coil belts by a mechanism somewhat similar to that shown at the right, but it is believed that the combination of parts herein shown and the peculiar and continuous process hereinafter set forth of simultaneously stretching and coiling a belt substantially during its process of manufacture has never before been attempted and that due to a peculiar coaction and inter-relation of these mechanisms a much better belt is obtained and in less time, in that the distensibility is permanently eliminated by one operation as will be hereinafter explained.

The method of using an apparatus of this character is substantially as follows: The belt is woven through or positioned upon the several sets of rollers 1, 2 and 3 and then led under the roller 20 and partially wound upon a solid core or mandrel 31 resting between the rollers 20 and 21, and held firmly thereagainst by means of the weighted pressure roll 27. The apparatus is then started and due to the peculiar coaction and inter-relation of the two groups of elements and the manner of connecting one with the other, whereby each roller or set of rollers has a greater peripheral speed than the previous roller or set in engagement, there is accomplished a pulling of the belt at all times whereby it is stretched and wound up very tightly.

By way of example, it may be noted that when the plies of canvas are sewed together to make a fabric belt, there is produced a very strong and firm article. A pull of many thousand pounds is required in order to stretch a twenty-inch ten-ply belt. This stretching cannot be successfully accomplished in a coiling device used by itself nor could it be successfully or practically accomplished by a belt stretching device alone such as shown at the left of the drawings, for example. If it is attempted to stretch the belt in a coiling device alone the coil could not be pressed downwardly upon the roll 21 with sufficient pressure to put the

required tension in the belt for the rollers would simply spin around against the face of the belt and shortly wear holes therein. With the calendering rollers or belt stretching device shown at the left of the drawings, this desired degree of tension is very easily exerted upon the belt because the belt is wrapped around the rollers through a major portion of their arcs and in addition to this, the sets of rollers are pressed together into biting engagement upon the belt as it passes therebetween. When sufficient sets are used it therefore is possible to stretch the belt the desired amount.

The set of calenders, constitutes a machine which enables the stretching of the belt with a tension sufficient to produce the initial desired result. The fabric in the belt, however, is very elastic and the instant it leaves the calender rollers, it tends to recover itself or shorten. When the belt is passed through the set of calender rollers arranged to run at differential speeds, such as above set forth to stretch the belt, it is then much easier to maintain this stretch, or, if it partially recovers, again to pull the belt to its stretched length than it would be if the belt had not been passed through the calender rolls. The result is that although the belt cannot be permanently stretched by either a coiling machine alone or a set of calender rolls alone, the stretch can be permanently removed by first passing the belt through a set of calender rolls and immediately coiling it in its stretched condition as described above.

It is impracticable to build an ordinary coiling machine which applies its power to the core with sufficient strength to coil a twenty inch ten-ply belt when the coil approaches its maximum diameter, for the reason that the power is applied to the center of the coil and the strain is applied to the circumference, but by using the coiling machine such as herein set forth, it is possible to maintain sufficient tension on the belt to prevent the belt previously stretched in a set of calender rolls from recovering on itself and therefore coil it in a stretched condition. After the belt has stood for a week or two coiled in this stretched condition it sets in such condition and the stretch is permanently eliminated.

It is thus seen that the present invention provides a simple and practical method of the above general character adapted to accomplish, among others, all of the objects and advantages herein set forth in a reliable, efficient and inexpensive manner.

Without further analysis, the foregoing will so fully reveal the gist of this invention that others can by applying current knowledge readily adapt it for various applications without omitting certain features that, from the standpoint of the prior art, fairly

constitute essential characteristics of the generic or specific aspects of this invention, and therefore such adaptations should and are intended to be comprehended within the meaning and range of equivalency of the following claims.

I claim:

1. The herein described method of treating belts which consists of separately stretching and then immediately simultaneously stretching and coiling said belts.

2. The herein described method of treating belts which consists of separately stretching and, then, immediately coiling said belts, while maintaining the resulting tension.

3. The herein described method of treating belts which consists of subjecting a belt to a series of roller devices having increasing peripheral speeds and coiling the belt when fed from said roller devices while maintaining the resulting tension.

4. The herein described method of treating belts which consists of subjecting a belt to a series of rollers having increasing peripheral speeds and coiling the belt when fed from said rollers by engagement with rollers having a higher peripheral speed than the first mentioned rollers.

5. The herein described method of treating belts which consists of subjecting a belt to a series of rollers having increasing peripheral speeds and then feeding the stretched belt to a coiling device while still under tension.

35 6. The herein described method of treating belts which consists of subjecting a belt to a series of rollers having increasing peripheral speeds and then feeding the belt into engagement with a pair of rollers one

of which has a higher peripheral speed than the other for coiling the same.

7. The herein described method of treating belts which consists of subjecting a belt to a series of rollers having increasing peripheral speeds, and then feeding the belt to a pair of rollers one of which has a higher peripheral speed than the other and both a higher speed than the stretching rollers for coiling the belt therebetween.

8. The herein described method of treating belts which consists of stretching a belt by a series of rollers having increasing peripheral speeds, and then feeding the belt to a pair of rollers for coiling the belt therebetween, one of which rollers has a higher peripheral speed than the other, and both a higher speed than the stretching rollers, and simultaneously pressing the coiling belt toward said last pair of rollers.

9. The herein described method of treating belts which consists of separately stretching and then simultaneously stretching and coiling a belt by continuously subjecting the belt to a series of calendering and pulling devices.

10. The herein described method of treating belts which consists of stretching and then simultaneously stretching and coiling a belt by continuously subjecting the belt to a series of calendering and pulling devices each of which has a more rapid action upon the belt than the preceding one.

In testimony whereof I affix my signature in the presence of two witnesses.

WILLIAM H. BRADSHAW.
